(57) **CLAIM**

The ornamental design for a drawing board, as shown and described.

DESCRIPTION

FIG. 1 is a front perspective view of a drawing board, showing my design.

FIG. 2 is a front elevation view thereof.

FIG. 3 is a rear elevation view thereof.

FIG. 4 is a left side elevation thereof.

FIG. 5 is a right side elevation thereof.

FIG. 6 is a top plan view thereof.

FIG. 7 is a bottom plan view thereof; and,

FIG. 8 is an enlarged view of an area labeled 8 in FIG. 4. The broken lines in the drawings depict environmental structure and boundaries and form no part of the claimed design.
